Patented July 29, 1919.

UNITED STATES PATENT OFFICE.

JOHN J. OLSON, OF BELVIEW, MINNESOTA.

STOVE ATTACHMENT.

1,311,705.

Specification of Letters Patent. Patented July 29, 1919.

Application filed October 26, 1917. Serial No. 198,629.

To all whom it may concern:

Be it known that I, JOHN J. OLSON, a citizen of the United States, residing at Belview, in the county of Redwood and State 5 of Minnesota, have invented certain new and useful Improvements in Stove Attachments, of which the following is a specification.

This invention relates to stoves and has 10 more especial reference to an improved cooking and heating attachment for gaseous and liquid fuel burners.

The invention has for its principal object to provide a device which may be arranged 15 over a gas or liquid fuel burner and used as a cooking or heating stove.

Another and equally important object of the invention is to provide a device of the character mentioned having means arranged 20 therein whereby a direct or indirect heat may be applied to the matter placed in the same, in order that it may be cooked in various ways, such as baked, roasted, fried, etc.

It is also an object of the invention to provide 25 a stove attachment which by slight adjustment, can be caused to serve as a highly efficient heater.

The improvements in the details and arrangement of parts will be apparent from 30 an inspection of the accompanying drawings in connection with the specific description hereinafter contained, and wherein the preferred embodiment of the invention is disclosed for the purpose of imparting a 35 full understanding of the same.

In the drawings:—

Figure 1 is a front elevation of the improved device,

Fig. 2 is a vertical longitudinal section 40 therethrough, and,

Fig. 3 is a vertical transverse section through the same.

Having more particular reference to the drawings and in connection with which like 45 reference characters will refer to corresponding parts throughout the several views thereof, 1 represents the housing of the device in its entirety, the front portion thereof of being open and provided with vertically 50 and horizontally movable doors 2 and 3, which doors as will be noted, are hinged thereto as at 4 and are provided with suitable catches 5 whereby the same may be maintained in closed positions, thus, serving

to effectively close the open front portion of 55 said housing 1.

The bottom of the housing is provided with spaced seats 6 in which gaseous or liquid fuel burners indicated by the numeral 7 may be placed. Pivotedly secured to the 60 housing bottom at points in proximity to the several seats 6 are flame spreading devices 8, which as will be noted, have the central portions thereof formed substantially cone like in order that the flames given off by the 65 burners will be spread in a manner to cause an indirect application of the heat to various food stuff or like material arranged in the housing. It will be noted in this connection, that the devices 8 may be readily 70 swung to upright or inoperative positions, shown and when so positioned, will permit the heat given off by the burners 7 to be directly applied to the material arranged in 75 the housing.

Arranged over the intermediate portion of the housing 1 is a horizontal partition 9 having an opening formed therein, which opening is adapted to be closed by a hingedly mounted cover 10 conforming thereto 80 in shape.

Foraminated racks 11 are removably arranged upon brackets 12 secured to the side walls of the housing 1 at points in proximity to the top thereof and serve as means 85 for supporting various food stuff and like material in the same for cooking.

Arranged adjacent the rear wall of the housing 1 is a vertically disposed flue or chimney 13 having branches 14 tapped 90 thereto throughout its length, which branches communicate with suitable openings formed in the rear wall of the housing and have dampers 15 rotatably mounted therein. Obviously, by so engaging the flue 95 13 with the housing an exhaust for the combustible fumes given off by the burners and the obnoxious odors given off by foodstuffs arranged in the housing is provided.

In using the improved device as a cooking stove, certain of the dampers 15 are opened to permit the fumes to be exhausted from the housing. Should it be desired to fry the food stuff or cook the same in a manner requiring the application of direct 100 heat thereto, the flame spreading device 8 is moved to its upright or inoperative position and the hinged cover 10 swung from 105

- over the opening formed in the partition 9. The pan or other utensil containing the food stuff may be then arranged over the opening and cooked to the desired point. It will be also understood, that the cover 10 may be arranged over the opening formed in the partition and the food stuff containing receptacle placed thereon. For baking and like cooking processes, an indirect heat is desired and accordingly, the device 8 is swung downwardly over its adjacent burners 7, whereupon the material may be either arranged on the partition 9 or on the foraminated racks 11 removably supported in the upper portion of the housing 1. During the cooking process, the fumes and odors may be exhausted from the housing by properly adjusting the dampers 15 arranged in the branches 14.
- 20 When it is desired to use the device for heating purposes alone, all dampers 15 with the exception of the lower one are closed and as a consequence, waste of heat is avoided. If desired, the horizontally and vertically moving doors 2 and 3 may be opened to permit the direct escape of heat from the

housing. However, when the same are closed, it is obvious that the heat will be radiated from the same.

Manifestly, the construction shown is capable of considerable modification and such modification as is within the scope of my claim, I consider within the spirit of my invention.

35 I claim:—

A device of the character described including an oven housing having spaced burner receiving seats formed in its bottom, flanged inverted cone-shaped deflectors pivoted to said bottom and capable of being 40 swung downwardly over the burner receiving seats, a flue connected to and communicating with said oven by way of one of the walls thereof at spaced points throughout the same, dampers interposed in the connections between said flue and the wall of said housing whereby to control the exhaust of heat and gases from the housing.

45 In testimony whereof I affix my signature hereto.

JOHN J. OLSON.
